a corporation of Massachusetts

Application August 1, 1939, Serial No. 287,829

12 Claims. (Cl. 175—41.5)

The present invention relates to electrical condensers, and more particularly to novel means and processes for improving the stability of condensers. The invention will be described in connection with condensers of the type commonly known as trimmer condensers, which find their chief application as semi-adjustable means for tuning the resonant circuits of radio receivers to fixed selected frequencies.

Such trimmer condensers comprise as their main elements two electrodes disposed adjustably with respect to each other with a dielectric layer, for example, a sheet of mica, interposed between same. Usually the electrodes and the interposed dielectric form a stack which is secured to a suitable base of low-loss insulating material.

The chief drawback of present-day trimmer condensers is that they are difficult to adjust to and do not retain their desired capacity setting.

Since the instability in capacity both with regard to initial setting and temperature variations is more pronounced the higher the capacity setting of the condenser, it has been the practice to operate trimmer condensers within a range limited by the so-called "working" capacity value. The "working" capacity of a trimmer condenser, however, is much less than is its maximum obtainable capacity, and to obtain satisfactory stability, in many cases, for example, in the compression type of trimmer condenser, only 40% to 50% of the inherent capacity range of a condenser can be utilized.

I have found that the instability exhibited by prior trimmer condensers is attributed to several factors. One of these factors is the difference in the physical hardness between the metal electrodes and the dielectric, for example, mica. This causes the electrodes to cut or wear into the dielectric at their contacting portions particularly when there is a change in their relative position either due to adjustment or to expansion and contraction of these parts because of temperature changes.

A second factor which I have found to contribute to the instability of condensers, is the high friction coefficient between the dielectric and the electrodes. Because it initially resists any relative movement of the parts, this friction sets up lateral stresses therebetween, which subsequently may be removed either wholly or in part, or not removed at all, bringing about an unpredictable change in the capacity of the condenser.

A third factor contributing to the instability of prior trimmer condensers is due to the imper-

fect contact between the electrodes and the dielectric due to the microscopically rough surfaces of the electrodes and the air pockets which are formed in the minute crevices of such rough surface. By expanding and contracting with changing temperature, the air so held changes the contact area between the electrodes and the dielectric and also the effective thickness of the dielectric. Because of this the condenser exhibits a high temperature coefficient of capacity, and furthermore because of the imperfect contact between the electrode and the dielectric, the full capacity of the condenser cannot be realized.

My invention obviates the above-recited drawbacks and insures a great degree of stability in capacity. This I achieve by interposing between the electrodes and the dielectric an electrical conducting material which is soft, non-thermoplastic, has a low coefficient of friction, and maintains its desirable properties, wear and atmospheric influences notwithstanding.

Such a material, of which there are a number but of which I have found a suitably deposited graphite particularly advantageous, I dispose as a substantially unaltering and lasting coating or layer on the surface of the electrodes in a manner hereinafter to be more fully described.

Such interposition of a soft electrical conducting material of great permanency and having a low coefficient of friction, between the surfaces of the electrodes and the dielectric, brings about the desired high degree of stability of a trimmer condenser because of the following:

First, the soft material so interposed between the electrodes and the dielectric, serves as a buffer or cushion between these elements and prevents the sharp ragged surface of the electrodes from physically contacting with and cutting into the dielectric.

Secondly, the soft conducting material fills the minute crevices of the electrode surface, eliminating air pockets and such large capacity changes as are otherwise brought about by the expansion and contraction of the air due to temperature changes.

Thirdly, the use of a material having a low coefficient of friction permits unimpeded movement of the electrode and dielectric relative to each other and eliminates lateral stresses and hysteresis in these elements which would be otherwise set up during adjustment of the capacity of the condenser or during the expansion and contraction of the surfaces caused by changes in temperature.

In addition to a high stability, several other

important advantages are achieved by means of my invention. For example, due to the intimate molecular contact which it provides throughout the contacting surfaces of the electrodes and the dielectric, my interposed soft conducting layers give higher maximum capacity values than have otherwise identical condensers lacking such layers.

Furthermore, because of the high degree of stability at even the maximum capacity setting, the full capacity range of the condenser can be actually utilized in practice.

As the material for the soft electrical conducting layer having the above requirements I have found graphite the most suitable. However, other conducting materials, for example, lead peroxide, magnetite, etc., can also be used.

To obtain the benefits of these materials and to maintain these desirable properties thereof, it is essential and so part of this invention, to so provide the layers comprising same that they retain their function and desirable properties unaltered during the life of the condenser.

I have found, for example, that if graphite is merely smeared or applied by one of the usual processes to the metal electrodes, it will gradually loosen from the coated surface and part of it will actually deposit on the dielectric, thereby defeating the purpose of the invention by decreasing rather than increasing the stability of the condenser.

Moreover, graphite layers so provided are affected by moisture and atmospheric condition, nor do they adhere to the edges and burrs of the electrode plates and therefore lack the protective features aimed at. To insure the permanency of the coating and its other desirable properties such as moisture resistance, the coating has to be applied to the electrode by a method which renders it well adhering to the electrode plate so as to form an integral coating thereon. A method which suggests itself is to mold the graphite or similar material with a suitable binder around the electrode. However, this method has the drawback that only comparatively thick coatings can be formed and these introduce an undesirable ohmic resistance in the condenser.

The process which I have found in every way satisfactory for applying such coatings and for obtaining permanency in their desired characteristics is by means of cataphoretic deposition.

My invention will be further described with reference to the appended drawing, in which:

Figure 1 is a cross-sectional view of a trimmer condenser embodying my invention.

Fig. 2 is a top plan view of the condenser of Fig. 1.

Fig. 3 is an enlarged cross-section of a portion of one of the metal electrodes of the condenser of Figs. 1 and 2, provided with a conducting layer or coating in accordance with the invention.

Referring now to Figs. 1 and 2, the condenser shown therein comprises a base 10 of "Bakelite," "Isolantite," or other suitable low dielectric loss insulating material. Disposed on the base 10 is a fixed electrode plate 11 and a resilient metal electrode plate 12. The plates 11 and 12 are each provided with a surface coating of a soft non-thermoplastic, low-friction electrical conducting material 13 and are to be later more fully referred to.

Interposed between the plates 11 and 12 is a layer of a suitable dielectric material 14, for example, a sheet of mica.

The design of the electrode plates 11 and 12 may conform with any accepted practice. As shown, the fixed electrode plate 11 comprises two integral portions 26 and 27. The portion 26 is the effective portion of the electrode whereas the portion 27 serves as one terminal for the condenser.

The electrode 12 is fixedly held to the base 10 by means of a rivet 28 or other attachment means which passes through the base 10, the portion 26 and the dielectric 14.

The adjustable electrode plate 12 consists of a substantially flat portion 26, two arched flexing members 21-21, a supporting and mounting portion 22, and a terminal portion 23.

The portion 26 forms the effective portion of the electrode and its capacitative relationship to the electrode plate 11 is varied by changing the effective distance between these plates; the arched members 21-21 imparting the necessary resiliency or "spring" to the portion 26.

Suitable electrical connection to the plate 12 is made by means of the terminal 23 which consists of a rectangular member disposed in a plane substantially perpendicular to the portion 26.

The plate 12 is held to the base 10 by means of a rivet 24 which passes through the base 10, the dielectric 14, and the mounting portion 22. The said mounting portion is integral with the terminal portion 23 and projects perpendicularly therefrom whereby its position in the assembly of the condenser is in the same plane as the flat portion 26.

The base 10 is provided at one end with a raised portion 25 of a height corresponding to the thickness of the fixed electrode 11 whereby the dielectric member 14 presents a level surface to the bottom face of the electrode 12.

For the flexing of the plate 12 there is provided a metal adjustment screw 15 having a head 16. Interposed between the screw head 16 and the flexible plate 12 is a washer 17 which may be either of metal or of an insulating material. The screw 15 threaded engages a nut 18 provided in a recess 19 of the base 10.

The electrode 12 is provided centrally at its portion 26 with an aperture sufficiently large to permit non-contacting passage of the adjustment screw 15. A similar aperture is provided in the portion 26 of the electrode 11.

The electrodes 11 and 12 as previously described, as provided with an integral surface coating of a soft non-thermoplastic, low friction electrical conducting material, and preferably of graphite. A coating provided in accordance with my invention is shown in Fig. 3 in which a metal electrode shown in portion as 30, has disposed about it a coating 13 which fills the crevices of its microscopically rough surface.

In Fig. 3, the rough character of the electrode surface and the thickness of the coating 13 has been exaggerated for the purposes of illustration.

The graphite coating 13 is provided preferably on both electrodes of the condenser; however, I have found that a high degree of stability in the condenser is achieved even if only the adjustable electrode 12 is provided on its surfaces with such a coating.

To achieve a condenser of high stability in accordance with the invention, the coating 13 must be integral with and permanently adhering to all portions of the electrode surface. A process which I have found in every way satisfactory to obtain such a coating is by cataphoretic deposition such as described in detail in the copending applica-

tion of Preston Robinson and Stanley O. Dorst, S. N. 197,692, filed March 23, 1938.

To adapt the said process for the purpose of the present invention, I prepare a coating solution comprising one part of the commercial product known as "Aquadag" or a similar suspension of graphite having imparted to it colloidal properties by the addition of a peptizing or emulsifying agent such as tannic acid, in ten to twenty parts of distilled water. The electrode to be coated is made the anode in a coating cell to which the suspension has been added. By the application of approximately 40 volts to the cell for approximately one second a uniform graphite coating of from .0001" to .0004" thick, is deposited on the surface of the electrode.

The voltage used and the time of deposition may, of course, vary from that above recited. In general, the thickness of the coating deposited is roughly proportional to the voltage and the time of deposition whereby to obtain a coating of a given thickness in a shorter time, a correspondingly higher voltage must be used.

It should be noted that by the use of cataphoretic deposition the coating so obtained covers not only the flat surfaces but also covers to the same depth or more all edges, corners, and burrs of the electrode.

The coating in general should have a thickness of at least the order of magnitude of the burrs or other microscopic roughnesses which exist on the electrode to be coated.

Coatings having a thickness greater than above recited may also be used, however, I have found that thick coatings may tend to peel and flake from the surface of the electrode. Moreover, since the material comprising the coating has generally a lower electrical conductivity than the underlying electrode metal the use of thick coatings tends towards an increase in the power factor of the condenser.

The coating so deposited is dried to remove the small quantity of water contained on its surface and then baked to the underlying electrode metal in a suitable oven heated to a temperature of approximately 150° C.

The baking at 150° C. may take place for one-half to one hour or more at the end of which time it is found that the graphite coating is of great permanency and does not brush off the surface of the coated electrode. Nor will the immersion of such a coating in boiling water for a period of fifteen mintues or even more cause it to loosen and part from the surface of the electrode.

The reasons for these remarkable properties in the coating of my invention I do not fully understand, however, I believe important contributing factors to be that the graphite particles are oriented partly at least in the same direction by the electric field during their cataphoretic deposition, and that the structure of the coating so obtained is preserved by the baking and by the removal or destruction of the emulsifying agent during the baking.

Trimmer condensers the electrodes of which are provided in accordance with my invention, with a soft non-thermoplastic electrical conducting coating having a low coefficient of friction, exhibit a high degree of stability when compared with condensers of similar mechanical construction lacking such electrode coatings.

By the provision thereof, I have been able, for example, to increase the stability of a given type of trimmer condenser otherwise exhibiting er-

5 ratic unpredictable capacity changes of from .75% to 4% to a uniform predictable change of approximately 2% to 5%. The condensers so compared were subjected after an initial setting of their capacity value to two heat cycles of 5 from 25° C. to 60° C.

Trimmer condensers the elements of which comprise dissimilar materials will on heating and cooling exhibit a temperature coefficient of capacity due to the change in dimensions of the elements. Condensers of the prior art even apart from the previously described factors bringing about their instability, exhibit different capacity values at a given temperature depending on whether the temperature is approached from 15 above or below. This phenomenon is called hysteresis. Condensers the electrodes of which are provided with an integral coating in accordance with my invention are singularly free from hysteresis. 20

Moreover, whereas in prior trimmer condensers it is necessary to make several readjustments of the capacity adjustment means to obtain the desired capacity value, a condenser provided with the coating of the invention is free of this draw- 25 back and its desired capacity value can be established by a single adjustment of the adjustment means.

Furthermore, partly because of the intimate contact provided between the contacting surfaces of the electrode and the dielectric, and partly because of the unimpeded movement of these elements brought about by the coating, the same torque—a torque of one inch pound—applied to the adjustment means produces nearly 35 80% more capacity.

Because of the high degree of stability achieved the working capacity range of the condenser can be extended to this capacity value.

It is thus evident that by means of my novel 40 invention, I have been able not only to increase the stability of the condenser and its maximum capacity value but also its maximum utilizable capacity as well.

While I have described my invention by means 45 of a specific example and in a specific embodiment, I do not wish to be limited thereto for obvious modifications will occur to those skilled in the art without departing from the spirit and scope of the invention. 50

What I claim is:

1. In a condenser, two electrodes, and a dielectric layer interposed between same, said electrodes provided on the engaging surfaces thereof with an integral coating of a soft non-thermoplastic electrically conducting material having a low coefficient of friction. 55

2. In an adjustable condenser, two electrodes with means for adjusting their relative position and a dielectric layer interposed between said electrodes, means to increase the stability of said condenser, said means comprising a soft non-thermoplastic electrically conducting material having a low coefficient of friction integrally disposed on said electrodes and interposed between the engaging surfaces of said electrodes and said dielectric. 65

3. In a trimmer condenser an electrode provided on its active surfaces with an integral coat- 70 ing of graphite.

4. In a trimmer condenser a stationary electrode, an adjustable electrode and a dielectric layer interposed between same, said electrodes provided on the engaging surfaces thereof with 75

an integral coating of graphite .0001" to .0004" thick.

5. In a trimmer condenser a fixed electrode, an adjustable electrode and a dielectric layer interposed between said electrodes, and means to prevent said electrodes from cutting into said dielectric, said means comprising a layer of an electrical conducting material which is softer than said dielectric integrally disposed on said 10 electrodes and interposed between said electrodes and said dielectric.

6. In a trimmer condenser a fixed electrode, an adjustable electrode and a dielectric layer disposed between said electrodes, and means to permit unimpeded lateral movement of said electrodes with respect to said dielectric, said means comprising an electrical conducting material having a low coefficient of friction integrally disposed on said electrodes and interposed between 20 said electrodes and said dielectric.

7. In a trimmer condenser a fixed electrode, an adjustable electrode and a dielectric layer interposed between said electrodes, means to permit an intimate contact between said electrodes and 25 said dielectric said means comprising a layer of an electrical conducting material which is softer than said dielectric integrally disposed on the engaging surfaces of said electrodes.

8. In a trimmer condenser, a fixed electrode, 30 an adjustable electrode and a dielectric layer interposed between same, an integral coating of graphite disposed on the surface of at least one of said electrodes and interposed between said electrode and said dielectric layer, said coating

remaining substantially uneffected when subjected to immersion in boiling distilled water.

9. In a trimmer condenser, a fixed electrode, an adjustable electrode and a dielectric layer interposed between same, an integral coating disposed on the surface of one of said electrodes and interposed between said electrode and said dielectric layer, said coating comprising graphite the particles of which have been oriented on the surface of the electrode by the action of an electric field. 5

10. A hysteresis free adjustable condenser, comprising two electrodes with means for adjusting their relative position, a dielectric layer interposed between said electrodes and an integral coating of graphite disposed on one of said electrodes and interposed between said electrode and said dielectric layer. 15

11. In a trimmer condenser, a fixed electrode, an adjustable electrode and a dielectric layer interposed between same, an integral coating of graphite devoid of emulsifying agents disposed on the surface of at least one of said electrodes and interposed between said electrode and said dielectric layer. 20

12. In a trimmer condenser, a fixed electrode, an adjustable electrode and a dielectric layer interposed between same, said electrodes having surfaces with microscopic roughnesses, and an integral coating of graphite having a thickness of 25 at least the height of said roughnesses provided on the engaging surfaces of said electrodes. 30

PRESTON ROBINSON.
